PACKAGING MACHINE

George Arlington Moore, New York, N. Y., assignor to National Biscuit Company, New York, N. Y., a corporation of New Jersey

Application November 2, 1945, Serial No. 626,283

9 Claims. (Cl. 226—14)

1

My invention relates to packaging machines and particularly to a machine for packaging biscuit or other flat articles in trays or boxes such as shown in my U. S. Patent No. 2,541,173, Packaging, which was issued February 13, 1951.

Automatic packaging of biscuit has long been sought and attempted but satisfactory results have not been attained heretofore, particularly with soda crackers and the like, principally because the packaging apparatus could not always measure off an exact volume or length of crackers for filling the cartons. Soda crackers are fragile and have very irregular and rough surfaces. The thickness of individual crackers from the same sheet or peel may vary from $\frac{1}{16}$ to $\frac{3}{8}$ inch. This makes it impossible always to fill a carton of definite length with a prescribed weight or count of crackers unless some cartons are slack filled and others filled too snugly. For example, a soda cracker may be sold in packages holding approximately 4 oz. The package may be approximately 8 inches in length and hold a minimum of 18 crackers to make the desired weight. But because of irregularities in the thickness of the crackers, the number required to fill the package may vary from 18 to 21. This variation in thickness and count has made it impracticable heretofore to package soda crackers by automatic means. Also crackers fresh from the oven are very fragile articles and must be handled delicately or excessive breakage will result.

The embodiment of my invention that I have illustrated is adapted particularly for accurate packaging of soda crackers, without breakage or loss of crackers, yet always filling the cartons within allowable limits. It is, of course, admirably adapted for packaging other products that are of relatively uniform size and thickness and not so fragile, such as snaps, cookies, wafers and other articles.

Reference is now made to the drawings for a complete understanding of the invention.

Fig. 1 is a diagrammatic representation of the entire machine.

Figs. 2a, 2b and 2c together form a front elevation of the entire machine.

Figs. 3a and 3b together form a rear elevation of the machine.

Fig. 4a is a diagrammatic representation of the carton feed.

Fig. 4b is a diagrammatic representation of the cracker feed.

Fig. 5 is a detail view showing how the flights enter or penetrate into the row of crackers to measure off a length sufficient to fill a carton.

2

Fig. 6 shows how the loading plunger pushes each successive measured quantity of crackers into a carton.

Fig. 7 shows the cracker feeding index cam.

Fig. 8 shows the loading plunger operating cam.

Fig. 9 shows the cam for operating the carton flap spreaders.

Fig. 10 shows the cam for operating the carton locator.

Fig. 11 shows the carton bank stop cam.

Fig. 12 shows the index lock cam.

Fig. 13 shows the cam for operating the safety pad or pusher.

Fig. 14 shows the cracker elevator lifting cam.

Fig. 15 shows the cam for lifting the flights so that they enter into the row of crackers.

Fig. 16 shows the meter regulator cam.

Fig. 17 shows the cam that operates the presser for holding down the crackers on the metering belt.

Fig. 18 is a development of all the cams showing their order or sequence of operation.

I will first describe the operation of the machine by reference to the diagrams on Figs. 1, 4a and 4b.

Fig. 1 is a diagram, in front elevation, of the entire machine while Fig. 4a is a diagram in side elevation of the box or carton feed and Fig. 4b is a side elevation of the cracker feeding means.

Referring to Figs. 1 and 4a, the cartons are fed to the right hand or lower end of a continuously driven belt 20 passing around pulleys 21, 22. This belt may be inclined as shown in Fig. 1 or horizontal as in Fig. 4a. The cartons preferably are open sided trays and are fed in a continuous stream or bank to the right hand end of the belt. At one point in their travel, the leading carton is engaged by a stop 23 which

checks forward movement of all cartons behind it. At proper times, the stop 23 is raised to release the leading carton which is carried forward by the belt until it engages a second stop 24 which locates the carton in position to be filled with crackers. At this point, which may be called the loading station, a pair of spreader fingers 25, 26 spread the carton lips slightly outward and square up the carton so that the charge of crackers can be inserted. When the carton has been filled with crackers it is released by raising the stop 24 and then carried on by the belt to be discharged over the pulley 22 to a delivery chute or packing table for further operations.

It will be noted that there is a gap between the leading carton that is held by the stop 23 and the carton at the filling station so

that there is no pressure of the string of cartons on the belt against the carton that is being filled.

Referring now to Figs. 1 and 4b, crackers are supplied in a continuous stream stacked on edge to the continuously driven conveyor 27. The crackers are fed from the conveyor 27 to two compensating belts 28, 29, which preferably have corrugated rubber surfaces to prevent slippage of the crackers and are driven intermittently at variable speeds to keep in balance a uniform flow from constant to intermittent supply. From the compensator belts, the crackers are fed to a metering belt 30 which likewise has a corrugated rubber surface and is driven intermittently at variable speeds. The metering belt 30 is driven from a pulley 31 keyed to a shaft carrying a grooved pulley 32. The pulley 32 is driven by a belt 33 from the pulley 34 and the speed of the metering belt 30 is varied during each cycle by raising and lowering the regulator pulleys 35. The total distance that the metering belt 30 travels during each cycle determines the length of the stack of crackers that is intercepted between each pair of flights. This distance may be varied by adjustment of the relative sizes of the pulleys 32, 34, which preferably are adjustable V-groove pulleys. Thus to fill a box 8 inches long, the length of crackers supplied to the flights usually will be about 7 $\frac{1}{2}$ inches, but due to variations in the crackers, or changes in the variety to be packed, this length may vary between 7 $\frac{1}{2}$ and 7 $\frac{1}{4}$ inches or more.

The pulley 34 is keyed to a shaft carrying a sprocket 36 over which the flight carrying chain 37 runs and a pulley 38 over which the belt 39 runs. The chain 37 and belt 39 also pass over a sprocket 40 and a pulley 41, respectively, fixed to a shaft that is driven intermittently by an index mechanism presently to be described. The chain 37 carries a number of flights 42 which are spaced the proper distance apart to intercept charges or measured amounts of crackers from the continuous stack 43 just sufficient to fill one of the cartons. These flights rise from the lower run of the chain 37 and enter between abutting crackers of the continuous stack adjacent an elevator 44 which is operated in proper timed relation with the metering belt 30 to loosen up or slack off the stack of crackers so that the flights can enter, as will be more fully described.

Referring now to Fig. 4b, the crackers 43 are fed continuously in stacked relation to the continuously driven belt 27. This belt delivers the crackers to the intermittently driven variable speed compensators 28, 29, which carry the crackers forward to the metering belt 30. The metering belt 30 delivers the crackers to the elevator 44 which is raised in proper timed relation to permit the flights 42 to enter between the crackers as best shown in Fig. 5.

In the embodiment of the invention illustrated, it is assumed that the boxes or trays are 8 inches in length and the distance between the flights 42 is equal to the length of the box. The metering belt 30 is regulated so as to deliver a stack of crackers slightly less than 8 inches in length between each pair of flights. The flight carrying chain 37 and belt 39 are driven intermittently or with a step by step movement so that the flights with charges of crackers measured off between them travel step by step and are stationary when they come opposite the loading station where the cartons or trays are held by the stop 24 and the flaps are spread open by the spreader fingers 25, 26. At this point a plunger 45 is operated

to push the charge of crackers into an empty carton that is opposite it on the belt 20 at the loading station. As the plunger 45 is withdrawn, the flights are moved forward another step to bring the next charge of crackers into loading position opposite the next carton which has been released by the stop 23 and carried forward to the stop 24 while the filled carton was being carried away by belt 20.

At the point where the flights enter between the crackers, I provided a soft pad or pusher 46 which is actuated in proper timed relation to gently push or pat back into line any cracker which may have been raised by entry of a flight 40. The metering belt 30 is operated intermittently and starts up at relatively high speed. In order to prevent the metering belt from slipping under the crackers, I use a corrugated belt and also provide a soft presser 47 which is brought down into engagement with the top of the stack of crackers just before the metering belt starts its forward movement so that there is no slippage of the crackers with respect to the belt. The speed of the belt 30 is regulated so that it will deliver a stack of crackers about 7 $\frac{1}{2}$ inches long to each pair of flights 42 which are spaced 8 inches apart. This always insures the flights being able to enter between crackers in the stack and to intercept a sufficient amount to fill the cartons within allowable limits. At the time a flight 42 is raised to enter between crackers, the metering regulator 35 is lowered so that the metering belt 30 is given a slight retrograde or backward movement which slacks off the crackers on the elevator 44 so that if the flight on rising comes beneath a cracker rather than between two, the cracker can fall either backward to the elevator or forward of the flight depending upon whether its center of gravity is to the rear of or forward of the flight.

Referring now to Figs. 2a, 2b and 3a, 3b, all of the parts and mechanisms of the machine are driven from a single shaft 48 which is driven from the drive pulley 49 through gears 50. A clutch 51 actuated by a lever 52 may be interposed in the shaft drive. The shaft 48 extends the full length of the machine and at its forward end has a pair of bevel gears 53 driving a shaft 54 carrying a sprocket that drives a chain 55 which in turn drives a shaft 56 to which the pulley 22 is secured for driving the carton carrying belt 20. Thus the belt 20 is driven continuously when the clutch 51 is engaged.

The shaft 48 carries a number of cams 57, 58, 59, 60, 61, 62, 63, 64, 65, 66, 67, which function in proper timed relation to drive the several parts of the machine.

The cam 57 drives the index head 88 (Fig. 3a) which is keyed to a shaft 69 to which the sprocket 40 and pulley 41 are secured for driving the flight chain 37 and cracker carrying belt 39. The chain 37 drives the sprocket 36 which is fixed to a shaft 70 that extends across the machine and at its opposite end carries the grooved pulley 34 (Fig. 3b) over which the belt 33 runs to drive the grooved pulley 32 that is keyed to a shaft 71 to the opposite end of which the pulley 31 is secured for driving the metering belt. The shaft 71 has a sprocket 72 (Fig. 2b) for driving a chain 73 that passes over a sprocket 74 keyed to the shaft 75 of the rear pulley 76 of the metering belt. A second sprocket 77 (Fig. 3b) on the shaft 75 drives a chain 78 which in turn drives the shaft of the compensator belt 29. The compensator belt 28 is similarly driven by chain and

sprockets from one of the shafts of the compensator 29. It will thus be seen that all of the parts for advancing the crackers from the time they are received from the conveyor 27 until they are in position to be pushed into the cartons are operated from the index head 68.

The cam 57 (Figs. 3a and 7) has a groove 79 in which a roller rides that is secured to one end of a bell crank 80 pivoted on the frame of the machine, the other end of the lever being pivotally connected to a link 81, the lower end of which is connected to the short arm 82 of a bell crank that is secured to a shaft mounted in a bearing 83 on the base of the machine. The arm 84 of this bell crank is connected at its upper end to a rack 85 which meshes with a pinion 86 that is loosely mounted on the shaft 69. The pinion 86 carries a spring pressed pawl 87 that is adapted to engage one of three teeth or shoulders on the index head 68. A slide 88 for guiding the rack 85 is mounted to rock about the shaft 69 so that there is no binding between the rack and its cooperating gear. When the cam 57 rocks the arm 84 to the left as viewed in Fig. 3a, the pawl 87 will engage one of the teeth of the ratchet 68 and turn the shaft 69 so as to carry the flights 42 and the metering belt and compensators belts through one cycle of movement. When the arm 84 is rocked to the right (Fig. 3a) the pawl 87 rides loosely over the ratchet so that there is no movement of the parts. The stroke of the rack 85 and consequently the rotation of the gear 86 is a little greater than the distance that the pawl moves the ratchet forward on each stroke so that there is some lost motion at the beginning of the forward stroke. It is necessary that the pawl advance the ratchet and its connected parts an exact amount at each operation and leave the flights properly positioned before the plunger 45. In order to insure that all the parts will stop in the exact required positions, I provide an index lock which is best shown in Fig. 3b. This lock comprises the disc 90, which is keyed to the shaft 70 and has three tapered notches or tooth spaces, each of which is adapted to be engaged by a locking finger 91 that is pivoted on the frame of the machine and has a tapered nose or single tooth adapted to fit closely in one of the tapered notches to stop and lock the disc in exact position. The finger 91 is pivoted to the frame of the machine and is pulled into engagement with one of the tooth spaces by a spring 92. It is retracted by the cam 62 (Figs. 3b and 12). A roller 93 on the lower end of an arm 94 rocks an arm 95 that is connected to a link 96 through which the cam 62 pulls the finger out of the tapered notch at the proper time. The cam 62 is timed so as to release the finger 91 prior to the time that it enters one of the tooth spaces and the spring 92 holds the finger in engagement with the disc until a tooth space comes opposite the finger so that it can snap into position. The cams 57 and 62 are timed so that the finger 91 will snap into the lock and hold the parts at the instant that the rack 85 and index head 68 are at the ends of their forward or working strokes. This stops a pair of flights with a measured quantity of crackers directly in front of the carton that is held by the stop 24 and fingers 25, 26 on the belt 20 ready to receive the crackers.

As soon as the flights holding a measured quantity of crackers stop in front of the empty carton, the pusher 45 is actuated by the cam 58 to push the crackers into the carton and is then quickly withdrawn. As shown in Figs. 2a, 3a 75

and 8, the cam 58 has a race 97 in which a roller on the lower end of a pivoted arm 98 runs. The arm 98 is connected to a link 99 that extends from the rear to the front of the machine where it is connected to the lower end of a short arm 100 that is fixed to a short shaft 101 to which the lower end of a long arm 102 is fixed, the upper end of this arm being fixed to the shank 103 of the plunger 45, (Fig. 6). A link 104 parallel to the arm 102 is connected to the shaft 103 so as to impart a parallel motion to it.

I will describe the functions and operation of each of the cams 59 to 67, in the order in which they are mounted on the shaft 48.

The cam 59, as shown in Figs. 2a, 3a and 9, operates the spreader fingers 25, 26. A lever 105 pivoted on the frame of the machine has a roller 106 at its lower end that rides on the cam 59. At its upper end the lever is connected to a link 107, the opposite end of which is connected to one arm of a bell crank 108 supported on the frame of the machine. The other end of the bell crank is connected to a link 109 which in turn is connected to a crank 110 secured to a shaft 111 that is rotatably mounted in brackets 112 adjacent the carton conveyor 20. The shaft 111 has two bevel gears 113, 114 which mesh with gears 115, 116 on short transverse shafts to which the fingers 25, 26 are fixed.

The cam 60 operates the carton stop 24, Figs. 2a, 3a and 10. A lever 117 pivoted to the frame of the machine carries a roller 118 at its lower end that rides on the cam 60 and at its upper end is connected by a link 119 to an arm 120 that is fixed to a short shaft 121 mounted in a bearing on the machine frame. At its opposite end, the shaft 121 carries an arm 122 that actuates the stop 24.

The next cam 61 (Figs. 2b, 3b and 11) operates the carton bank stop 23. A lever 123 pivotally supported on the frame carries a roller 124 at its lower end in contact with the cam 61. At its upper end the lever is connected to a link 125 which in turn is connected to one arm of a bell crank 126, the other arm being connected to a link 127 that is connected to a crank 128 fixed to a short shaft 129 to which the stop 23 is attached.

The next cam 62 actuates the index locking finger 91 as previously described.

The cam 63 controls the pusher 46, Figs. 2b, 3b and 13. An arm 130 pivoted on the machine carries a roller 131 which is held in contact with the cam 63 by a spring 132. A push rod 133 has a lost motion connection with a pivoted arm 134 which actuates the pusher pad 46. The rod 133 positively raises the pad 46 but when the roller 131 rides off from the dwell of the cam 63 the spring 132 pulls the rod 133 and pad 46 down to the top level of the biscuit.

The cam 64 operates the elevator 44, Figs. 2b, 3b and 14. A bell crank 135 pivotally supported on the frame has a roller 136 engaging the cam 64 and has one arm connected to the lower end of a link 137, the upper end of which is connected to a crank 138 that is connected to a sleeve rotatably mounted on a short transverse shaft 139. This sleeve carries a cam 140 which engages a roller 141 on a lever 142 beneath the elevator 44 as best shown in Fig. 2b. The lever 142 at its free end has a roller 143 which rides on the under side of the elevator 44 to raise it. As best shown in Fig. 2b, the contour of the cam 140 is such that the elevator starts to rise very slowly so that

there is no danger of throwing the crackers from the elevator as it rises.

The cam 65 operates to lift the flights 42 at the point where they successively enter between crackers in the stack. A bell crank 144 has a follower 145 running in a race in cam 65 and is connected to a link 146, the upper end of which is connected to a crank 147 secured to the shaft 139. The opposite end of the shaft 139 is connected to an elevator arm 148 (Fig. 2b) which is adapted to engage and lift the flights 42 when they are carried by the chain 37 into operative position beneath the stack of crackers.

The next cam 66 operates the meter regulator 35. A bell crank 149 has a follower 150 operating in the race of the cam 66 and is connected to a link 151, the upper end of which is connected to a lever 152, one end of which is pivoted on the shaft 71 and the free end of which carries the two regulator pulleys 35. Looking at the Fig. 3b, the rotation of the shafts 70, 71 is clockwise. These shafts are driven intermittently through the index head 63 when the lock 91 is released. When the regulator pulleys 35 are stationary, the metering belt 39 will be driven at uniform speed. When the cam 66 moves the regulator down, the metering belt 39 first stops and then slightly reverses its direction. In Fig. 3b of the drawings, the pulley 32 is driven counterclockwise by the belt 33 running over the drive pulley 34. In this position the regulator 35, which consists of two idling pulleys carried by the shiftable arm 152, serves to take up the slack on the top run of the belt 33 so that the pulley 32 will be driven at constant speed. At the instant the arm 152 commences its rapid swing lowering the pulleys 35 from their upper position the upper run of the belt 33 becomes slack, and the driving traction of the pulley 34 is used primarily for taking up the slack in the upper run of belt 33, thus effecting no positive drive on the pulley 32. Since the vertical movement of the rollers 35 is much faster than the linear speed of the belt 33, at the same time that slack is created in the upper run of the belt its lower run is being put under tension by the lower roller 35. This tension, exerted in a clockwise direction on the pulley 32, acts as a brake and momentarily stops the pulley. As the arm 152 continues to the end of its downward stroke and the regulator 35 tends to take up the slack created in the upper run in carrying the lower run of the belt in both directions, and the pulley 32, which has been stopped momentarily, is now pulled for a short interval in a clockwise or negative direction. At the instant the regulator 35 reaches its lower position and all the slack in both the upper and lower runs of belt 33 is completely taken up, pulley 32 is again momentarily stopped and then reversed to be driven again at constant speed in its original counterclockwise direction. When the regulator 35 is swung upward again, the pulley 32 will continue to rotate counterclockwise but will be accelerated momentarily due to the upward thrust on the upper run of belt 33, which in taking up the slack created in the lower run increases the linear speed of the upper run of the belt 33 and, hence, accelerates the speed of rotation of the pulley 32. When the slack in the bottom run of belt 33 is taken up, a momentary back lash motion is imparted to the pulley 32 in reducing it to its normal speed. This backward movement causes a slackening off or loosening of the crackers on the elevator 44. This retrograde motion of the metering belt takes place when the elevator 44 begins to rise; so that at the top of the rise the crackers

are stacked loosely and tilted away from the edge of the elevator as shown in Fig. 5. This loosening up of the crackers at that time enables the flights 42 to enter easily between the crackers in the stack.

The cam 67 operates the presser 47. A bell crank 153 has a roller 154 riding on the cam and is connected to the lower end of a link 155, the upper end of which is connected to the lower one of two parallel arms 156. The arms 156 at one end are pivoted to the bracket 157 secured to the frame of the machine and at the other end actuate the presser 47 so that the latter always remains in vertical position.

The operation of the flights 42 in measuring off definite volumes of crackers from the continuous stack and carrying them forward to the loading station is best shown in Figs. 2a, 2b and 5. Each flight 42 is connected to the free end of a flight arm 158, the other end of which is pivotally connected to the chain 37. Each flight arm at its free end adjacent the flight has a lateral extension 159 which runs on a track so as to guide the flights as they are carried by the chain 37 around the sprockets 36, 40. The flights 42 project upwardly and laterally from the arms so that they extend over the belt 39 on the upper run of the chain. Each of the lateral extensions 159 has a flattened end 160 which on the upper run of the chain engages in a slotted track 161 which holds the flights 42 in vertical position. The track 161 ends just beyond the station where the carton is filled as shown in Fig. 2a. From that point on around the sprocket 40 the flights 42 and arm 158 are free to pivot about their connection to the chain 37. However, a curved guide or track 162 is provided to hold the flight as it passes around the sprocket. On the lower run of the chain, the extensions 159 run on a horizontal track 163 until they approach the sprocket 36. At this point the track 163 curves down and around the sprocket 36 as shown at 164 in Fig. 2b. As each flight comes up and around the guide 164, the flight lifting arm 148 is in its lowered position and when the flight comes to rest at the end of one cycle of movement of the index head, the arm 148 will be brought up so as to engage the extension 159. In Fig. 2b the chain 37 is at rest and the arm 148 has just raised a flight 42 up so that it has passed between biscuits in the stack that have been fed forward by the metering device. The elevator 44 has been lowered and the parts are ready for the next cycle to carry the measured quantity of crackers between the flights on thru the next step. As soon as the flights start forward, the arm 148 is lowered so as to be ready to receive and raise the next flight. The arm 148, as shown in Fig. 2b, raises the flattened extensions 160 so that it is ready to enter and travel along the groove 161. Bridges 165, 166, 167 are provided to bridge the spaces between adjacent pulleys of the several belts and at the forward side of the metering belt pulley 31 there is a short bridge 168 leading to the elevator 44. Beyond the elevator 44 there is another bridge 169 along which the flights 42 and crackers travel to the upper run of the belt 39.

It will be noted on reference to Figs. 3a, 3b, that not only are all of the cams 57 to 67 mounted in alignment on a single shaft but all of the levers and arms which are actuated in the first instance by these cams have the same axis and are supported on a single shaft 170 that is fixed to the frame of the machine except for the single arm 153, the axis of which is in alignment with the

shaft 170. This arrangement of cams and levers makes for accuracy in timing and ease of construction. All functions of the machine are performed in proper sequence upon each complete rotation of the cam shaft 48.

Assuming that the index head 68 is stationary and that the rack 85 has just started its forward movement with the pawl 87 in engagement with a shoulder on the index head as shown in Fig. 3a, the index lock 91 is withdrawn and the meter regulator 35 will be in lowered position. The presser 47 will have been lowered into contact with the crackers over the metering belt, the pusher 46 will have been raised and a flight 42 will have been raised between the crackers as shown in Fig. 2b. Also the elevator 44 has been lowered and the plunger 45 has been fully withdrawn. Now as soon as the rack 85 continues its working stroke, the index head 68 starts to turn and the parts operate or function in the following order. Simultaneously with the forward movement of the flights 42, the flight arm 148 starts its downward stroke and the carton stop 24 starts to move in to engage the carton which has just been released by the stop 23. The carton flight spreaders 25, 26 then start to swing down so as to open the lips on the carton ready to receive the crackers. By this time a pair of flights are almost in front of the loading station and the plunger 45 starts its inward movement and the flight lifter arm 148 starts to lift the next flight. At substantially the same time the index lock 91 starts in to engage the lock so as to stop a pair of flights and quantity of crackers in loading position. The meter regulator pulleys 35 now start their downward stroke so as to move the metering belt 30 backwards to cause a slack in the stack of crackers as the cam 140 starts to raise the elevator 44. With the index head now locked in position the flight arm 148 continues to lift the flight and the cracker inserting plunger 45 starts to withdraw. The flight and lifting arm 148 are now fully raised and the pad 46 starts to descend to press back any crackers that may have been raised by upward movement of the flight. The carton bank stop 23 now starts to withdraw so that an empty carton can be fed forward. The carton flap spreader fingers are now fully raised and the stop 24 withdrawn so that the filled carton is carried forward by the carton carrying belt 20.

Next the metering belt regulator starts its upward stroke and the cam 140 lowers the elevator 44. The presser pad 47 then starts to lower so that it will be in engagement with the crackers by the end of the cycle. The presser pad 46 raises and the stop 23 engages the next carton in the spring on the belt 20. All these functions occur through one complete rotation of the cam shaft 48 and the parts are now back in position with the pawl 87 in engagement with the next shoulder on the index head ready to start another cycle.

Fig. 18 is a chart representing all of the cams 57 to 67 in the order and relationship in which they are secured to the shaft 48. The numbers of the cams are at the left of the several developments and the numbers at the right indicate the ultimate part that is actuated by each cam. The vertical lines indicate the degrees of the circle through which each cam rotates and their intersections with the rises and dwells of the several cam developments indicate the points in the cycle where each cam starts and ends its function.

In the diagram of Fig. 1, I have shown the

tray carrying belt 20, the flight carrying chain 31 and belt 39 inclined upward toward their delivery ends. However, these usually will be horizontal, but in some cases I prefer the upward slope as shown, because of the backward inclination that it gives to the crackers at the point where the flights enter.

In operation of the machine, the articles to be packed, such as crackers, are supplied in a continuous stack or bank to the continuously running conveyor 27. This conveyor delivers the crackers stacked on edge to the first compensator 28, which in turn delivers to the second compensator 29. The speed of the conveyor 27 is such as to assure a continuous and adequate supply of crackers to the machine.

The compensator 29 delivers to the metering belt 30, which is driven at such a speed as to deliver approximately 7½ inches of crackers to the flights 42 for each cycle of operation. The metering belt is driven intermittently at variable speeds through the pulley 31 and regulator 35. When the regulator 35 is moved up, the speed of the metering belt exceeds its normal or average speed and when the regulator is moved down the belt 33 is taken up so rapidly on its lower run that the pulley 31 is turned slightly backward. This takes place just at the time that the elevator 44 is raised and one of the flights 42 is entering between crackers in the stack just ahead of the forward end of the elevator 44. At this time elevator 44 is raised, as shown in Fig. 5, and the inclination of the elevator and backward movement of the metering belt 30 cause the crackers to tilt toward the rear and be held stationary on the elevator during the time that the flight 42 is rising. When the flight 42 has fully entered between the crackers, the pusher 46 is lowered so as to press back into line any crackers that may have been raised by upward movement of the flight.

The flights with measured quantities of crackers intercepted between each two then move forward with a step by step motion until two of the flights come directly opposite an empty carton or tray which is held open on the belt 20 by the spreader fingers 25 and 26. The pusher 45 then moves inward and pushes this measured quantity of crackers into the box. The box is then released by the stop 24 and is carried forward by the belt 20 over the pulley 22 and slides down a chute to the packing table or wrapping machine.

The embodiment of my invention illustrated is designed particularly for filling cartons such as shown in my Patent No. 2,541,173. These cartons as shown in Figs. 4a and 6, comprise open sided trays, 170, which have outwardly extending lips 171, 172, at each end of the open side. When a tray is positioned at the loading station by the stop 24, the spreader fingers 25 and 26 square up the trays and bend the lips 171, 172 slightly outward so that the charge of crackers 43, held between the flights can be pushed into the carton by the pusher head 45.

Instead of the belt 39, which carries the charges of crackers along in cooperation with the flights 42, other suitable means may be used.

An important feature of my invention resides in the continuously driven belt 27, the compensator 28, 29 and metering belt 30, which cooperate to convey the bank of crackers to the flights 42 and change their continuous motion on belt 27 to controlled intermittent motion whereby

each space between flights is filled with a predetermined definite volume of crackers or other articles sufficient to fill one box or tray. Each of the compensator belts 28, 29 is driven intermittently and at variable speeds, the average linear speed of belt 28 being slightly greater than belt 27 and that of belt 29 exceeding belt 28. Thus the crackers are somewhat looser in the stack on belts 28, 29 than they are on belt 27. When the metering belt 39 is moving forward at its maximum speed, which follows the lowering of elevator 44, there is a tendency to open up a gap in the line of crackers being fed to it. Except for the compensators, the gap could open wide enough to permit the crackers to fall over so far that they could not be righted by pressure of the on-coming column of crackers fed by belt 27. When belt 39 is moving forward at its maximum speed, there usually will be a loosening up of crackers on the compensators as indicated at 173, 174, Fig. 4b.

While I have shown the crackers 43 stacked on edge in a continuous bank, in some types of packages the crackers will be carried in stacks three or four high on the belt 27, or of whatever height is necessary to fill a carton and then the flights 42 will intercept or measure off a sufficient number of these vertical stacks to make up the length of the inside of the carton.

My invention is capable of many other modifications and adaptations, all of which I claim that may come within the scope or terms of my claims.

Having thus described my invention what I claim and desire to secure by Letters Patent is:

1. In a packaging machine, the combination of a conveyor for carrying forward a continuous bank of articles stacked on edge, an endless chain having upper and lower runs, spaced flights on said chain, means cooperating with said flights as they rise from the lower to the upper run of the chain to enter them between articles in said bank and fill the spaces between adjacent flights with measured quantities of the articles, means for causing periodic backward movement of the articles in the bank at the point where each flight rises whereby the articles are loosely stacked to permit entry of the flight, a second conveyor for carrying open faced boxes forward parallel to said flights on their upper run, means for positioning the boxes opposite the filled spaces between the flights, and means for transferring the measured quantities of articles from between the flights into the boxes on the second conveyor.

2. In a packaging machine, the combination of a continuously driven belt adapted to carry a continuous line of open faced cartons having outwardly extending lips at each end of their open faces, two stops spaced apart a distance slightly greater than the length of a carton, means for moving said stops into and out of the path of the cartons on the belt whereby the first stop will hold the line of cartons out of contact with a carton held by the second stop, and a pair of spreader fingers adapted to engage and hold the lips outward on the carton that is stopped by the said second stop.

3. In a packaging machine, the combination of a metering device, means for supplying articles in a continuous bank to one side thereof, means for operating the metering device intermittently to advance the articles therethru, an elevator adapted to receive the articles from the metering device, an endless carrier having upper and

lower runs with its upper run adjacent to said elevator, spaced flights mounted on said endless carrier and adapted to enter between articles in the bank as they rise from their lower to their upper run adjacent to the elevator, and means for raising the elevator while each flight enters between articles.

4. In a packaging machine, the combination of a metering device, means for supplying articles in a continuous bank to one side thereof, means for operating the metering device intermittently to advance the articles therethru, an elevator adapted to receive the articles from the metering device, an endless carrier having upper and lower runs with its upper run adjacent to said elevator, spaced flights mounted on said endless carrier and adapted to enter between articles in the bank as they rise from their lower to their upper run adjacent to the elevator, and means for raising the elevator and causing backward movement of the metering device while each flight enters between articles.

5. In a packaging machine, a continuously driven belt adapted to carry articles in a continuous bank, an intermittently operated metering device adapted to receive the articles carried by said belt and carry them on in the same direction, and compensating means comprising a variable speed conveyor unit between the metering device and belt for creating slackness in said bank of articles when said metering device is carrying articles forward and for taking up the slack when said metering device is not carrying articles forward.

6. In a packaging machine, a continuously driven belt adapted to carry articles in a continuous bank, a metering device adapted to receive and regulate the rate of flow of articles from the belt, means for periodically driving said metering device faster and rearward and holding it stationary with respect to said belt, and compensating means comprising a variable speed conveyor unit between the meter and belt for feeding articles to the metering device faster than they are supplied by the belt when the metering device is driven at its faster speed, said compensating means taking up the excess supply of articles from the belt when said metering device is driven backward or is stationary.

7. In a packaging machine, a continuously driven belt carrying a continuous bank of articles stacked on edge, a metering device including a shiftable belt tightener to which the belt delivers the stacked articles for regulating the rate at which the articles are delivered, an endless chain having upper and lower runs with its upper run in alignment with said metering device, spaced flights on said chain adapted as they pass from the lower to the upper run to enter between the stacked articles delivered by the metering device and measure off definite quantities of articles therefrom, and means including an elevator platform hinged at its entrant end for interrupting the flow of articles through the metering device when a flight is entering between articles.

8. In a packaging machine, the combination of a continuously driven belt carrying a continuous bank of articles in continuous motion, a series of intermittently driven spaced flights beyond said belt adapted to enter between articles in said bank and measure off definite quantities thereof between the flights, and means between the belt and flights including an elevator platform hinged at its entrant end to change the mo-

tion of the bank of articles from continuous to intermittent.

9. In a packaging machine, the combination of a continuously driven conveyor continuously carrying forward a continuous bank of articles, an endless chain having upper and lower runs, spaced flights on said chain travelling on the upper run in alignment with said conveyor and spaced therefrom, means for carrying the continuous bank of articles from the conveyor to the chain, said flights as they rise from their lower to their upper run being arranged and operated to enter between articles in said bank and fill the spaces between adjacent flights with measured quantities of the articles and means including an elevator platform hinged at its entrant end for slackening off the continuously carried articles in the bank at the point where the flights enter.
